(57) **CLAIM**

The ornamental design for a cooker, substantially as shown and described.

DESCRIPTION

FIG. 1 is a perspective view of the cooker in a closed position in accordance with the present invention;

FIG. 2 is a left side view of the cooker shown in FIG. 1;

FIG. 3 is a right side view of the cooker shown in FIG. 1;

FIG. 4 is a front view of the cooker shown in FIG. 1;

FIG. 5 is a rear view of the cooker shown in FIG. 1.

FIG. 6 is a top view of the cooker shown in FIG. 1.

FIG. 7 is a bottom view of the cooker shown in FIG. 1.

FIG. 8 is a perspective view of the cooker shown in FIG. 1 in an open position.

FIG. 9 is a front view of the cooker shown in FIG. 1 in an open position; and,

FIG. 10 is a top view of the cooker shown in FIG. 1 in an open position.
